UNITED STATES PATENT OFFICE.

JOHN WILLIAM COOK, OF MIAMI, FLORIDA, ASSIGNOR OF ONE-THIRD TO GEORGE A. WALDECK, OF MIAMI, FLORIDA.

ROCK-CUTTING MACHINE.

1,180,014.

Specification of Letters Patent. Patented Apr. 18, 1916.

Application filed June 25, 1915. Serial No. 36,285.

To all whom it may concern:

Be it known that I, JOHN WILLIAM COOK, a citizen of the United States, residing at Miami, in the county of Dade and State of Florida, have invented certain new and useful Improvements in Rock-Cutting Machines; and I do hereby declare the following to be a full, clear, and exact description of the invention, such as will enable others skilled in the art to which it appertains to make and use the same.

My invention relates to new and useful improvements in rock cutting machines and is more particularly an improvement over my former Patent No. 1,083,666, issued January 6, 1914, and my object is to provide a cutting device comprising a rotary cutter head and a plurality of cutting tools having a combined reciprocating and rotary movement.

A further object is to provide means for readily assembling the parts of the cutting device together.

A further object is to so construct the cutter head and tool holder that rocks or similar hard substances may readily pass through the cutting device. And a further object is to provide yielding operating means for the tool holder.

Other objects and advantages will be hereinafter set forth and more particularly pointed out in the accompanying specification.

In the accompanying drawings which are made a part of this application, Figure 1 is a side elevation of the supporting frame and cutting device attached thereto. Fig. 2 is a front elevation of the supporting frame and cutting device. Fig. 3 is an enlarged detail perspective view of one of the pitmen employed for reciprocating the tool holder, showing the cushioning mechanism therefor. Fig. 4 is a detail elevation of the tool holder. Fig. 5 is an enlarged sectional view through the tool holder and cutter head. Fig. 6 is a top plan view of the cutting device, showing the pitmen and rotating shaft in section. Fig. 7 is a bottom plan view of the cutter head. Fig. 8 is a side elevation thereof. Fig. 9 is a sectional view of the cutter head as seen on line 9, 9, Fig. 8. Fig. 10 is a side elevation of a ring member

employed for locking the parts of the cutting device together, and Fig. 11 is a bottom plan view thereof.

Referring to the drawings in which similar reference numerals designate corresponding parts throughout the several views, 1 indicates a supporting frame which may be constructed in any preferred manner, to one end of which is attached a disk 2, said disk having ears 3 thereon, with which the arms of the frame are secured.

Depending from the peripheral edge of the disk 2 is a flange 4, said flange having in its peripheral face a circumferential recess 5, with which engages an inwardly extending rib 6, of a collar 7, said collar being preferably formed of two semicircular members which are secured together by introducing bolts 8 through hollow bosses 9 at the meeting edges of the two sections. The lower edge of each collar section is provided with a T-slot 10 with which engages T-heads 11 on the upper edge of a cutter head 12, the edges 13 of the stems of the T-heads being beveled to receive the beveled faces 14 of the T-slots 10, said beveled portions being so arranged that the collar sections can be quickly attached thereto or removed therefrom.

The cutter head 12 comprises a circular shell portion 15, portions of which are cut away to provide passages 16, through which rocks or large particles may pass without interfering with the operation of the cutting device.

Attached to the lower edge of the shell 5 and preferably integral therewith is a plurality of arms 17, which arms are inclined downwardly and extended inwardly to the axial center of the cutter head, said arms at their point of junction having an opening 18 therethrough which is preferably square to receive the squared end 19 of a rotating shaft 20, said shaft being provided with an integral or fixed collar 21 which rests upon the inner face of the joining arms so that by extending bolts 22 through the collar and joined portions of the arms, the cutter head will be securely held in engagement with the shaft.

The arms 17 form a substantially conical spider, the inner faces of the arms having

stepped portions 23, through which are formed sockets 24 and through these sockets are adapted to reciprocate cutting tools or chisels 25, and while I have shown the 5 sockets 24 of square formation in cross section, it will be readily understood that they can be of any shape to conform to the shape of the cutting bars.

Slidably mounted upon the shaft 20 within 10 the cutter head 12 is a tool holder 26 which is likewise composed of arms 27 designed to register with the arms 17 of the cutter head. The lower edges of said arms have stepped portions 28 inversely arranged 15 with respect to the stepped portions 23 of the arms 17, said stepped portions having slots 29 in their lower faces in which are secured the inner ends of the cutting tools 25, pins 30 being extended transversely 20 through the walls of the slots and the interposed portions of said tools. By arranging the cutting tools in this manner, the tools nearest to the center of the cutter head will travel ahead of the next succeeding set of 25 tools and the second set of tools ahead of the next succeeding set, so that the tools will have a shearing effect when in operation.

By arranging the arms 17 and 27 in substantially spider formation and by providing 30 the opening 16 in the shell of the cutter head, any large particles, such as stone, or the like, will readily pass between the arms, and to better insure the free passage of such 35 obstructions, the upper edges 30 of the arms 27 are tapered while the disk 2 is provided with an enlarged opening 31 for the passage of such particles as may enter through the 40 passage in the cutter head.

The tool head 26 has a central vertical orifice 32, through which the rotating shaft 20 passes and in order to reciprocate the tool holder on said shaft, the head 33 is extended upwardly from the central portion of the tool holder which head is provided 45 with a peripheral groove 34 to receive a collar 35, said collar having wrist pins 36 thereon to which are pivotally secured one section of the pitmen 37, said pitmen in turn extending through the disk 2 on opposite sides of the rotating shaft 20.

The outer ends of the pitmen sections 37 are entered in sleeves 38 and are slidably mounted therein, the movement of said pitmen sections being limited by extending a headed stud 39 transversely through the end 55 of the pitmen sections entering the sleeve and through slots 40 in the sleeve, the length of the slot determining the longitudinal movement of the pitmen sections.

In order to form a cushion for the pitmen sections, a coiled spring 41 is introduced 60 into each sleeve between the closed end of the sleeve and the end of the pitman section, the tension of the spring being controlled 65 by means of an adjusting screw 42 which is

threaded through the closed end of the sleeve and engages a washer 42 between the closed end of the sleeve and the spring.

Extending beyond the closed end of each sleeve are a pair of ears 44, between which 70 are pivotally secured a pitman section 45, the upper end of the pitman section 45 being secured to a crank shaft 46, so that when said crank shaft is rotated the pitmen sections will operate to reciprocate the tool 75 head and tools carried thereby, moving them inwardly and outwardly through the sockets in the arms of the cutter head.

The crank shaft 46 is operated on a driving shaft 47 mounted in suitable bearings on 80 the supporting frame 1, said driving shaft having a beveled gear 48 which meshes with a beveled gear 49 on a stub shaft 50, said stub shaft extending at right angles to the driving shaft and having a gear 51 at the 85 outer end thereof which gear in turn meshes with a pinion 52 attached to the crank shaft 46, and it will be readily seen that when the driving shaft 47 is rotated, the crank shaft 46 will be likewise rotated through the 90 medium of the beforementioned gears. The rotating shaft 20 is operated by attaching the gear 53 thereto with which meshes a pinion 54 on the inner end of the driving shaft 47 and when said shaft 20 is rotated, 95 the cutter head 12, ring member 7 and tool holder 26 will be likewise rotated, while the disk 2 and parts carrying the same remain stationary.

Attached to the inclined faces of the arms 17 are cutting blades 55 which are designed primarily to shear off the particles loosened by the cutting tool, said cutting blades engaging the surface upon which the cutting 100 device is operated as the cutter head is rotated.

In operation, the cutter head is positioned against a surface and power applied to the driving shaft 47, which will result in operating the crank shaft 46 and reciprocating 110 the tool holder and tools on the rotating shaft, forcing the sharpened ends of the tools into engagement with the surface upon which the tools are to operate. As the tools move inwardly and outwardly the cutter head and parts carried thereby are slowly rotated, thereby constantly bringing the edges of the cutting tools into engagement with the new surface, and in view of the manner in which the cutting tools are positioned they form a shearing action upon the 115 parts with which they engage.

Should a stone or extreme hard substance be encountered, the force of the blow is cushioned from the crank shaft by the ends 120 of the pitman sections 37 striking the springs 41, thus eliminating the jar from the pitmen and parts operating the same. As the particles are loosened by the cutting tools, they enter through the passages in the shell 125 130

of the cutter head 12 and pass thence between the arms of the tool holder and through the opening 31 in the disk 2, the free end of the head 33 being preferably tapered similar to the edges 30 of the arms 27 so as to give a freer passage for the particles within the cutter head casing.

If it is desired to remove the tool holder or to replace any of the cutting tools, it is but necessary to remove the bolts 8 from the bosses 9 and the bolts 22 from the collar 21, when the two sections of the collar member may be separated and disengaged from the T-heads of the cutter head to permit the cutter head to descend from around the tool holder and tools carried thereby.

It will be fully understood that although I have shown and described a preferred means of operating the tool holder, any suitable means may be employed for operating the same.

Having thus fully described my invention what I claim as new and desire to secure by Letters Patent is:—

1. A cutting device, comprising a disk, means to support the disk, a depending flange on the disk, said flange having a recess, a cutter head having sockets therein, a reciprocating tool holder in the cutter head, tools carried by the tool holder and adapted to be moved longitudinally through said sockets, a two part collar having a rib adapted to engage the recess in the flange, means to secure the parts of the collar together, and interlocking means on the cutter head and

collar member to hold the cutter head in fixed engagement with the collar member.

2. A cutting device, comprising a hollow cutter head, inclined integral arms at one end of the head, said arms having stepped portions through which extend sockets, said cutter head having passages between the arms, a tool holder comprising arms having stepped portions coöoperating with the stepped portions of the cutter head, said stepped portions having slots, cutting tools secured in said slots and extending through the sockets of the cutter head, and means to reciprocate the tool holder and tools carried thereby.

3. A cutting device, the combination with a disk having a discharge opening therethrough, a depending flange at the edge of said disk, said flange having a peripheral recess, a cutter head having T-heads projecting therefrom, parts of the T-head being tapered, a two-part collar having T-slots, parts of the walls thereof being tapered to coöperate with the taper of the T-heads, an internal rib on the collar section adapted to engage the recess in the flange, and means to secure the collar sections together and around said flange.

In testimony whereof I have signed my name to this specification in the presence of two subscribing witnesses.

JOHN WILLIAM COOK.
